UNITED STATES PATENT OFFICE

AUDLEY R. CANFIELD, OF BOONE, IOWA

CEMENT BRICK AND BLOCK MACHINE

Application filed August 2, 1927. Serial No. 210,193.

This invention relates to improvements in cement brick and block machines, the primary object being the production of a machine which will meet the demand of brick and block makers and give a speedy, simple and economical all around machine at a minimum of cost and which will make bricks and blocks of different designs and dimensions. More particularly this machine is an improvement upon the cement block machine set forth in Patent Number 1,050,804, granted to me on the 21st day of January, 1913, and by the use of which only cement blocks are adapted to be made. By the use of my invention cement bricks and blocks of superior quality are adapted to be made easily in large quantity at less cost than heretofore. The machine also is easily and quickly convertible for use in making either bricks or blocks of different sizes and designs. It gives to the individual contractor and builder a machine by which he can produce his own bricks and blocks at a minimum of cost.

To these ends, my invention comprises the features of construction and combination of parts, hereinafter described and claimed.

In the accompanying drawings, forming part of this specification, Fig. 1 is a perspective view of my invention, showing the parts in position immediately after a group of cement bricks have been molded and the palette raised in readiness to remove the group of green bricks from the machine; Fig. 2 is a plan of my invention when the parts are set in readiness to mold a group of bricks, excepting that the hopper is removed; Fig. 3 is another plan when the brick plates and yoke are in superior position and the block plates or sides stripped from the machine, said yoke being partly broken away and in section; Fig. 4 is a vertical section on the line 4—4 of Fig. 2, the broken line position of the table indicating the folding position it is adapted to assume; Fig. 5 is another vertical section taken on the line 5—5 of Fig. 2; Fig. 6 is a side elevation of a detail showing the spider elevating operating handle; Fig. 7 is an end view partly in section of the structure shown in Fig. 6; Fig. 8 is a section on the line 4—4 of Fig. 2 of a detail of the structure when the brick plates and yoke are lowered in readiness for molding bricks, the palette and fillers being removed; Fig. 9 is a similar section to that shown in Fig. 8 when the brick plates and yoke are raised into superior position; Fig. 10 is a section of a detail showing the slicer handle in lowermost position after the brick plates have been forced forwardly to perform their slicing function; Fig. 11 is a perspective view of the typical removable block molding side plate; Fig. 12 is a section of a detail showing a core in the block mold for use in molding hollow building blocks; and Fig. 13 is a perspective view of one of the palettes for use when a hollow building block is molded in the machine.

In the drawings, A indicates a base frame of any suitable construction, upon the top 10 of which are mounted a plurality of side plates forming the front, back and end elements, respectively 11, 12, 13 and 14, of a mold. The back element 12 is rigidly secured in vertical position, to the base frame by bolts 15 and the remaining side elements are tiltably and detachably secured to said base frame by separable hinge connections, formed by pintles 16 in the top 10 and hinge seats 17 in the lower ends of arms 18 depending from said plates (see Fig. 8). In closed mold forming position all of the side plates are vertical (see Fig. 5) and after the molding operation the movable side plates tilt outwardly on their hinge connections and spread (see Fig. 9). A palette or mold board B, of any suitable design and thickness is placed at suitable height on the top 10 of the frame between the side plates to produce the bottom of the mold and upon which the block or bricks can be removed from the machine.

A horizontal shaft 20 is secured in a pair of bosses 21, along the outer wall of the back plate 12 and upon this shaft as a common axis are journaled a yoke element C, a group of brick plates D, and a table element E. The yoke element is adapted to swing down into substantially horizontal position, engaging over cam or draw shoulders 22 resembling reinforcing vertical ribs on the outer faces of the movable side plates 11, 13 and 100

14 and drawing the side plates closed into vertical mold forming position. A pair of arms 23, depending from the yoke, engage the draw shoulders on the front plate 11 in advance of the yoke proper so that the end and front plate will move together evenly. At end 24 on one side of the yoke C is adapted to strike a stop shoulder 25, projecting from the back plate, to limit the movement and hold the yoke in raised position as shown in Fig. 9. Handles 19 are provided for operating the yoke member.

The group of brick plates D is composed of a plurality of vertical plates extending forwardly through vertical slots 26 in the front and back plates 11 and 12 and in height corresponding with the width of the cement bricks to be molded on the palette in the machine. The back ends of these plates are held apart by the spacing blocks 27 and tied together by the tie bolt 28, which penetrates the plates and spacing blocks. The spacing blocks are slotted at 29 to permit the tie bolts being inserted freely.

The forward ends of the brick plates are spaced apart by the short sections of tubing 30 and a tie bolt 31 passing through said tubing and plates serves to clamp the plates and tubing together as a unit. The two outer brick plates extend sufficiently forward and are cut away to form handles 32 by which the group of brick plates can be raised and lowered by hand. The lower edges near the back end of the group of brick plates have a series of aligned angle slots 33 (see Fig. 8), opening downwardly to receive the shaft 20. The inner horizontal portions of these slots permit of the group of brick plates sliding for a limited distance forwardly and backwardly to assist in freeing the plates from the bricks on the palette without breaking the material from which the bricks in the mold cavities have been produced. The group of brick plates is adapted to swing up into substantially vertical position on the shaft 20 (see Figs. 1 and 8), suitable slots 34 in the table E being provided through which the brick plates turn. The back ends of the brick plates strike against the back member of the group of side plates when the brick plates assume superior position and limit this movement. When at rest in this superior position the shaft 20 is at the inner end of the slots 33 (see Fig. 9), and they remain in this position on the shaft after being swung down into horizontal molding position across the mold cavity as shown in Fig. 8. A handle 35 having two sides 36 and 37 journaled on the shaft 31 and formed with work arms 38 are employed for imparting a stripping movement to the brick plates D. When the brick plates are lowered the work arms 38 engage over the yoke C so that when the lever operating handle 35 is pressed down the brick plates are slid forwardly over the

shaft 20 to the back ends of grooves 33 (see Fig. 10), thus imparting a stripping movement to the brick plates. This stripping action produces a cleaner job of molding by the brick plates. Bevel shoulders 40 on the work arms 38 strike the upper side of the yoke element C when the group of brick plates is lowered into the mold and guide the stripping member into engagement over the yoke member in readiness for the lever handle 35 to be pressed down and the brick plates stripped forwardly. Cam disks 41 selectively positioned by binding screws 42 on the sides of the lever arms 36 and 37 are adapted to strike the ends of the adjacent brick plates D and limit the downward and upward movement of said lever arms. Suitable grooves 43 in the spacing tubing 30 are adapted to hold the lever members 36 and 37 freely so that they may turn without binding.

The table element E consists of a plate secured on brackets 45 which are journaled on the shaft 20. Table supporting arms 46, detachably engaging a corner of the base support are pivoted at 47 to the brackets 45. By releasing the table supports from the base support the table can be lowered or folded from the horizontal to the broken line position shown in Fig. 4. The table may be used for supporting the hopper when not in use or for any other purpose desired.

Arranged in the base frame is the palette lifting mechanism F, which is adapted after each molding and stripping operation to be used for raising the palette bearing the block or bricks into the position shown in Fig. 1, so that the palette can be easily lifted and carried from the machine. This lifting mechanism comprises a spider frame composed of four vertical thrust rods 51 sliding vertically through guide holes 52 in the top 10 of the base frame and mounted at their lower ends in skeleton frame 53. This skeleton frame has at its opposite ends pairs of antifriction guide rollers 54 (see Fig. 5), traveling in vertical channels 55 in the ends of the body frame A. Lifting cams, each made in two pieces 56 and 57 are secured to the square lifting shaft 58, said shaft being mounted in bearings 59 which are rotatably supported in the body frame. These cams are arranged to engage the skeleton frame 53 below antifriction rollers 60 and thrust the rods 51 upwardly. The cam member 57 of each lifting cam unit is pivoted at its heel end to member 56 by the bolt 61 and the outer end portions of members 57 are adjustably supported on members 56 by the stud bolts 62, to align the cam members and thus produce even lifting movement by the spider frame and preventing breaking of the blocks or bricks molded by the machine. The upper ends of the thrust rods are adapted to engage below and lift the palette in the

mold after the molding operation. This movement is imparted by turning the lifting shaft 58. This lifting shaft has secured to one end an operating handle 63 by the pin 64 (see Figs. 6 and 7). Clearance at 65 is provided so that the operating handle can be tilted on pin 64 longitudinally on the lifting shaft 58 and made to engage below a pin 66 on the body frame and hold the lifting mechanism in superior position with the palette in the mold elevated. The upper ends of the channels 55 are closed to house them and provided with shields 67 to protect the channels and the antifriction rollers 54 from sand, mortar or other material that might interfere with the movement of the parts.

The plate members 12, 13 and 14 are provided with springs 70 which detachably engage through slotted ribs 71 with said members to spread them and release the molded article or articles when the brick plates D and yoke C are elevated. The lower end of each of said springs 70 is vertically adjustable in a socket member 72 to which it is secured by a bolt 73 passing through a vertical slot 74 (see Fig. 4). Said socket member is adjustably secured to the top 10 to be selectively positioned on the base frame by bolt 75 passing through slot 76 in the socket member, thereby permitting the adjustment of the outward tendency of spring 70 (see Fig. 3).

When filling and tamping molding material in the mold cavity or cavities when either molding blocks or bricks, a hopper G may be placed over the top of the plate members and held in position by removable pins 78 entering recesses 77 in said members (see Fig. 4).

In use, assuming first that bricks are to be molded in the machine, suitable fillers 80 are set between the side plates and a palette B placed on said fillers, the thickness of the fillers causing the palette to assume a position in the plane of the lower sides of the bricks to be molded. The yoke C is next swung down into horizontal position, thus engaging and closing the side plates tightly together around the fillers and palette. The group of brick plates D is then swung down into horizontal position by its handles, the hopper G is next adjusted over the side plates, and the mold cavities are then filled and tamped with molding material. After removing the hopper and scraping any surplus material away from the surface, the stripping handle 35 is pressed down into the position shown in Fig. 10 and the stripping or horizontal movement thus imparted to the brick plates. This frees the plates so that they can be lifted into superior position away from the molded bricks without disturbing and breaking the material. The yoke is next raised and the side plates are spread automatically by their springs 70. The

handle 63 is swung up and the palette and fillers thus raised into the position shown in Fig. 1, whereupon the handle is made to engage the pin 66, and hold the palette and bricks in superior position, from which they are removed by hand or other means. The brick plates assume backward position automatically when raised so that when again lowered they are in readiness for the handle 35 to again impart the stripping movement when desired.

When the machine is used for molding blocks, the group of brick plates is lifted out of engagement with shaft 20 and removed from the machine. A palette is then placed in the mold cavity either with or without the use of a filler according to the design or size of block it is desired to mold. The machine is then used in the same manner as for molding bricks excepting without the use of the group of brick plates. It is contemplated to use a number of different kinds of detachable mold plates, varying in size and design, Fig. 11 illustrating only one of many forms. It is also contemplated to use a core 82 (see Fig. 12) in the mold, bolted at 83 to the base frame, in which event a hollow palette 84 is employed. The machine thus provides a simple and speedy means for use by the individual contractor or builder for making his own building blocks and bricks, at a minimum of expense.

In accordance with the patent statutes, I have described the principles of operation of my invention together with the apparatus which I now consider to represent the best embodiment thereof but I desire to have it understood that the construction shown is only illustrative and that the invention can be carried out by other means and applied to uses other than those above set forth within the scope of the following claims.

Having described my invention, what I claim as new and desire to secure by Letters Patent is:

1. A combined brick and building block molding machine, comprising, in combination, a suitable frame, a plurality of building block side walls mounted upon said frame, part of said side walls being hinged to spread after the molding operation, a brick supporting palette removably arranged between said walls, a plurality of brick plates between said walls and above said palette and adapted to cooperate therewith in molding a plurality of bricks, means for supporting said palette in brick molding position between said walls, said means being movable to raise said palette with the bricks thereon, and a yoke member adapted to close down over said hinged walls to hold them in block molding position, said yoke member and said brick plates being hinged on a common axis whereby they may be swung up out of cooperation with said side walls.

2. A combined brick and building block molding machine, comprising, in combination, a suitable frame, a plurality of building block side walls mounted upon said frame, 5 part of said side walls being hinged to spread after the molding operation, a brick supporting palette removably arranged between said walls and above said palette and adapted to cooperate therewith in molding a plurality of 10 bricks, means for supporting said palette in brick molding position between said walls, said means being movable to raise said palette with the bricks thereon, and a yoke member adapted to close down over said hinged side 15 walls to hold them in block molding position, said yoke member and said brick plates being hinged on a common axis whereby they may be swung up out of cooperation with said side walls and said brick plates having limited longitudinal slicing movement to assist 20 in stripping the bricks.

3. A brick molding machine, comprising, in combination, a suitable frame, a plurality of side walls mounted upon said frame, a 25 palette disposed between said side walls, a plurality of brick plates disposed between and cooperating with said side walls to mold a group of bricks on said palette, said plates being movable upwardly to clear the bricks 30 on said palette and longitudinally to assist in stripping the bricks.

4. A brick molding machine, comprising, in combination, a suitable frame, a plurality of side walls mounted upon said frame, a 35 palette disposed between said side walls, a plurality of brick plates disposed between and cooperating with said walls to mold a group of bricks on said palette, said plates being movable upwardly to clear the bricks 40 on the palette and longitudinally to assist in stripping the bricks and being detachably mounted upon said frame.

5. A brick molding machine, comprising, in combination, a suitable frame, a plurality of side walls mounted upon said frame, a 45 palette disposed upon said frame, a plurality of brick plates disposed between and cooperating with said side walls to mold a group of bricks on said palette, said plates being movable longitudinally while in brick 50 molding position to assist in stripping the bricks and upwardly to clear the bricks, and means for automatically imparting said longitudinal movement to said plates to strip 55 the bricks.

6. A brick molding machine, comprising, in combination, a suitable frame, a plurality of side walls mounted upon said frame, a palette disposed between said side walls, a 60 united group of brick plates disposed between and cooperating with said side walls to mold a group of bricks on said palette, said group of plates being movable longitudinally while in brick molding position and upwardly to 65 clear the bricks, and means for automatically

imparting said longitudinal movement to said group of brick plates to strip the bricks while they are being raised.

7. A brick molding machine, comprising, in combination, a suitable frame, a plurality of side walls mounted upon said frame having brick plate receiving slots, a palette disposed between said side walls, a united group of brick plates disposed through said slots and across said side walls and cooperating 75 with said side walls to mold a group of bricks on said palette, said group of plates being movable longitudinally while in brick molding position and upwardly to clear the bricks, and means for imparting said longitudinal movement to said group of brick plates automatically to strip the bricks while they are being raised.

8. A combined brick and building block molding machine, comprising, in combination, a suitable frame, a plurality of building block side walls mounted upon said frame, part of said side walls being hinged to spread after the molding operation, a brick supporting palette removably arranged between said walls, a plurality of brick plates between said walls and above said palette and adapted to cooperate therewith in molding a plurality of bricks, means for supporting said palette in brick molding position between said walls, 95 said means being movable to raise said palette with the bricks thereon, a yoke member adapted to close down over said hinged walls to hold them in block molding position, a table extending laterally from said machine and adapted to fold downwardly, said yoke member, brick plates and table being hinged upon a common axis whereby the yoke and brick plates may be swung up out of cooperation with said side walls and palette and said table elevated, and means for supporting 100 said table in elevated position.

9. A brick molding machine, comprising, in combination, a suitable frame, a plurality of side walls mounted upon said frame having brick plate receiving slots, a palette disposed between said side walls, a united group of brick plates disposed through said slots and across said side walls and cooperating with said side walls to mold a group of 110 bricks on said palette, said group of brick plates being provided with angle slots near their back ends, and a hinge support detachably engaging said group of brick plates through said angle slots, whereby the brick plates have swinging movement and longitudinal movement to strip the bricks molded upon said palette.

10. A combined brick and block molding machine, comprising, in combination, a suitable body frame, a plurality of block molding side walls mounted upon said body frame, part of said walls being hinged to spread after the molding operation, a yoke hinged 125 to swing down and engage the side walls and 130

hold them closed in block molding position, a palette arranged between said side walls, a spider frame slideable vertically in said body frame and adapted to raise said palette after the molding operation, cam mechanism co-operating with said spider frame to raise and lower the same, means for operating said cam mechanism, and a plurality of brick plates between said side walls and above said

10 palette and adapted to cooperate therewith to mold a plurality of bricks, said brick plates having angle slots in their back ends being hinged upon said body frame and adapted to swing back away from over the
15 palette and to simultaneously move longitudinally.

11. A combined brick and block molding machine, comprising, in combination, a suitable body frame, a plurality of block molding side walls mounted upon said frame, part of said side walls being hinged to spread after the molding operation, a yoke hinged to swing down and engage the side walls and hold them closed in block molding position,
20 25 a palette arranged between said side walls, track channels extending upwardly in said body frame, a spider frame slidably vertically in said track channels and adapted to

raise said palette after the molding operation, cam mechanism cooperating with said spider frame to raise and lower the latter, means for operating said cam mechanism, and a plurality of brick plates between said side walls and above said palette and adapted to cooperate therewith in molding a plurality of bricks, said brick plates having angle slots in their back ends being hinged through said slots upon said body frame and adapted to swing back away from over the palette and to simultaneously move longitudinally.

12. A combined brick and block molding machine, comprising, in combination, a suitable body frame, a plurality of block molding side walls mounted upon said frame, part of said side walls being hinged to spread after the molding operation, a yoke hinged to swing down and engage the side walls and hold them closed in block molding position, a palette arranged between said side walls, track channels extending upwardly in said body frame, a spider frame having guide rollers slideable vertically in said track channels and adapted to raise said palette after the molding operation, shielding means over the upper ends of said track channels, cam mechanism cooperating with said spider frame, to raise and lower the spider frame, means for operating said cam mechanism, and a plurality of brick plates between said side walls and above said palette and adapted to cooperate therewith in molding a plurality of bricks, said brick plates having angle slots in their back ends and being hinged throughout said slots upon said body frame and adapted

to swing back away from over the palette and to simultaneously move longitudinally.

13. A combined brick and block molding machine, comprising, in combination, a suitable body frame, a plurality of block molding side walls mounted upon said frame, part of said side walls being hinged to spread after the molding operation, a yoke hinged to swing down and engage the side walls and hold them closed in block molding position, a palette arranged between said side walls, track channels extending upwardly in said body frame, a spider frame having guide rollers movable upwardly in said track channels and adapted to raise said palette after the molding operation, a shaft journaled in said body frame, cams adjustably carried by said shaft to evenly engage and lift said spider frame, means for turning said shaft, and a plurality of brick plates between said side walls and above said palette and adapted to cooperate therewith in molding a plurality of bricks, said brick plates having angle slots in their back ends and being hinged through said slots upon said frame and adapted to swing back away from over the palette and to simultaneously move longitudinally.

14. A molding machine, comprising, in combination, a suitable body frame, a plurality of block molding side walls mounted upon said frame, part of said side walls being hinged to spread after the molding operation, a yoke hinged to swing down and engage the side walls and hold them closed in block molding position, a palette arranged between said side walls, track channels extending upwardly in said body frame, a spider frame having guide rollers movable upwardly in said track channels and adapted to raise said palette after the molding operation, a shaft journaled in said body frame, cams adjustably carried by said shaft to evenly engage and lift said spider frame, means for turning said shaft and a plurality of brick plates between said side walls and above said palette and adapted to cooperate therewith to mold a plurality of bricks, said brick plates having angle slots in their back ends and being hinged through said slots upon said body frame and adapted to swing back away from over the palette and to simultaneously move longitudinally.

In witness whereof, I have signed my name to this specification.

AUDLEY R. CANFIELD. 120
